DESIGN FOR A GAME BOARD

John Sneal, Vancouver, British Columbia, Canada

Application January 24, 1941, Serial No. 98,374

Term of patent 14 years

To all whom it may concern:

Be it known that I, John Sneal, a citizen of the Dominion of Canada, residing at 715 Robson St., in the city of Vancouver, in the Province of British Columbia, Dominion of Canada, have invented a new, original, and ornamental Design for a Game Board, of which the following is a specification, reference being had to the accompanying drawing, forming a part thereof.

The figure is a plan view of a game board showing my new design.

The article is of no appreciable thickness.

I claim:

The ornamental design for a game board, as shown and described.

JOHN SNEAL.
